UNITED STATES PATENT OFFICE.

BURNHAM C. STICKNEY, OF ELIZABETH, NEW JERSEY, ASSIGNOR TO UNION TYPEWRITER COMPANY, OF JERSEY CITY, NEW JERSEY, A CORPORATION OF NEW JERSEY.

TYPE-WRITING MACHINE.

No. 917,809.

Specification of Letters Patent. Patented April 13, 1909.

Application filed June 6, 1902. Serial No. 110,452.

To all whom it may concern:

Be it known that I, BURNHAM C. STICKNEY, citizen of the United States, and resident of Elizabeth, in the county of Union and State of New Jersey, have invented certain new and useful Improvements in Type-Writing Machines, of which the following is a specification.

This invention relates to writing machines in which a cylindrical platen is geared to a line space wheel, and especially where one function of the gearing is to cause the platen to rotate differently from the line space wheel, so that the impression lines upon the platen overlap, whereby the surface of the platen is subjected with substantial evenness to the type blows, and its smoothness is preserved, enabling the machine to make clear type impressions for an indefinite time.

One object of the present invention is to put the gearing into compact form and also to house it, thereby enabling it to keep clean, and also conducing to the neat appearance of the machine.

Another object is to provide for utilizing the same gearing for effecting fine rotative adjustment of the platen and the paper thereon, thereby causing a single set of gears to perform two distinct operations.

Another object is to improve the means for effecting automatic longitudinal reciprocations of the platen; and other objects will hereinafter appear.

My invention consists in certain combinations of devices, features of construction and combinations of parts, all as will be herein-after more fully set forth and particularly pointed out in the concluding claims.

In the accompanying drawings, Figure 1 is a plan of a platen and its appurtenances constructed in accordance with my improvements. Fig. 2 is a partly sectional elevation of the right-hand end of the platen and frame. Fig. 3 is an enlarged sectional plan of the right-hand end of the platen and its appurtenances. Fig. 4 is a cross section taken on the line $x-x$ of Fig. 3 and looking toward the right. Fig. 5 is an enlarged perspective view of the line space wheel and certain parts rigid therewith, and also of a set of bearing rollers upon which said wheel turns. Fig. 6 is an enlarged face view of an internal gear which is secured to the platen. Fig. 7 is an enlarged detail showing a method of con-

necting two pinions by a tongue and groove, so as to form a double pinion. Fig. 8 is an enlarged side view of a crank and a double pinion carried thereby. Figs. 9 to 21 inclusive show another form of platen rotating mechanism. Fig. 9 is a sectional plan of the platen and its appurtenances. Fig. 10 is a plan, partly broken away, of the platen and certain parts rigid therewith. Fig. 11 includes face and sectional views of an internal gear which is attached to the platen. Fig. 12 shows respectively face, edge and sectional views of an internal gear and a peripheral cam which are rigid with the line space wheel. Fig. 13 includes end and side views, the latter partly broken away, of a sleeve carrying an eccentric, and also a hand wheel whereby the sleeve is operated. Fig. 14 is a fragment of the device shown at Fig. 12, showing one way of mounting a brake so as to produce frictional opposition to the rotative movements of the platen, whereby accidental rotative displacement of the latter may be prevented. Fig. 15 includes face and side views of a collar which is mounted upon the eccentric sleeve shown at Fig. 13. Fig. 16 shows face and edge views of a simple washer, and Fig. 17 like views of a split washer, the latter being employed to prevent accidental rotation of the thumb wheel which is used to effect fine rotative adjustments of the platen. Fig. 18 is an enlarged view of one end of the eccentric sleeve shown at Fig. 13, and of a pinion carried thereon. Fig. 19 is a face view of the pinion seen at Fig. 18. Fig. 20 is an enlarged face view showing the two internal gears shown respectively at Figs. 11 and 12, and also the Fig. 19 pinion in mesh with both thereof and mounted upon the eccentric which is shown at Fig. 13. Fig. 21 is an enlarged view of the internal gear which is attached to the platen and is shown in the background at Fig. 20.

Throughout the several views, similar parts are designated by similar characters of reference.

A cylindrical platen sheath 1 of rubber or other material is mounted upon a wooden core 2, the latter being provided at its left-hand end with a head 3 having a hub 4, and at its opposite end with a head 5 having a hub 6, said heads being secured to the core by screws 7, and said hubs fitting upon a platen shaft 8, which is journaled in end bars

9 and 10 of a platen frame, and carries upon its projecting ends thumb wheels 12 and 13, whereby the platen may be rotated in the usual manner.

5 Referring particularly to Fig. 3, it will be seen that the right-hand platen head 5 lies within the sheath 1, the core 2 being shortened to make room for said head and other portions of the platen-actuating mechanism.

10 An internal gear 14 is formed upon a drum or shell 15, which fits within the sheath 1, and abuts against the platen head 5, the drum and head being both secured to the platen core 2 by the screws 7. The line space 15 wheel, which is designated as 16, is provided with a companion internal gear 17, the wheel having an inwardly extending rim portion 18, and said gear being attached to the edge of the rim by screws 19. Meshing with the 20 platen gear 14 is a pinion 20, and meshing with the line space gear 17 is a concentric pinion 21 rigid with the pinion 20, thus forming a double pinion, which is pivoted upon the free end of a crank 22. Said crank may 25 turn about the platen shaft 8, being provided with a long actuating sleeve 23 through which said shaft extends, and wherein the shaft may rotate. The line space wheel is mounted upon the sleeve 23, by means of 30 bearing rollers 24, which run within an elongated hub 25 formed upon the line space wheel. Said sleeve 23 is reduced in diameter at 26 so as to take a bearing in the right-hand bar 10 of the platen frame, and also has a 35 threaded projecting portion 27, upon which is clamped by means of a tangentially arranged screw 28 (Fig. 4) the split hub 29 of a finger wheel 30. The finger wheel, sleeve and crank 22 are held stationary during the 40 ordinary line-spacing movements of the platen, by means of a brake or friction washer 31, which works between said hub 29 and a loose washer 32 placed upon the sleeve 26 and bearing against the outer side of the 45 platen frame. Said spring draws a shoulder 23^a upon the sleeve against a washer 33 placed against the inner side of the platen frame, thus tending constantly to prevent rotation of the wheel 30, sleeve 23 and crank 50 22. The line space wheel is confined between the washer 33 and the crank 22.

At Figs. 1 and 2 are illustrated the usual line space pawl 34 and lever 35, the latter being provided with a projection 36, which 55 at the line spacing operation engages one of the notches in the line space wheel, and locks the wheel and platen against overthrow. The pawl 34 normally stands out of engagement with the line space wheel, and the latter is provided with the usual spring check 60 37, which serves to position the line space wheel and platen after they have been rotated.

It will be observed that the platen gear 14 65 is provided with forty-eight teeth, while the

line space wheel gear 17 has forty-nine teeth; while the pinion 20, which meshes with the platen gear, has twelve teeth, and the pinion 21, which meshes with the line space gear 17, has thirteen teeth. As will be understood by reference to Figs. 3 and 8, these pinions or double pinion is freely mounted upon a pin 38 carried upon the crank 22; and that the diameter of the pinion 21 is a trifle greater than that of the pinion 20, while that of the gear 17 has the same excess over that of the gear 14.

When rotative force is applied to either of the finger wheels 12 and 13, it is transmitted through the shaft 8 and the left-hand platen 70 head 3 to the body of the platen, which communicates through the described gearing a rotative movement to the line space wheel. When, on the other hand, power is applied directly to the line space wheel by the driving pawl 34, movement is communicated through said gearing to the platen. There is, however, a slight difference between the velocity of the platen and that of the line 75 space wheel.

During the ordinary rotation of the platen at the line feeding operation, the crank 22 remains stationary, being held against rotation by the brake or spring washer 31; and hence the pinion 21 is rotated by the line 80 space gear 17, while the pinion 20, which rotates uniformly with the pinion 21, effects the rotation of the gear 14 and hence of the platen. By reason of the smaller diameter of the pinion 20, the velocity of the platen 85 rotation is caused to fall below that of the line space wheel, which is the preferred construction. It will be understood, however, that the invention includes movements of 90 this character in which the platen is caused to creep ahead of the line space wheel, although the present construction permits the employment of fewer teeth on the line space wheel, thus enabling the spring check 95 100 105 110 115 120 125 130 to operate more effectually.

Since the pinion 20 has twelve teeth and the platen gear 14 has forty-eight, it follows that said pinion makes four revolutions at each revolution of the platen; and hence the gear 17 is caused to revolve through a distance corresponding to four revolutions of the thirteen-tooth pinion 21, or in other words, to make a movement equal to fifty-two teeth, which is $1\frac{3}{49}$ revolutions. In other words, the speed of the line space wheel is to that of the platen as $1\frac{3}{49}$ is to 1, or as 1 is to $49/52$. Thus while the line space wheel, which always moves through aliquot parts of a revolution, is making one complete revolution, the platen makes $49/52$ of a revolution; and supposing that thirty-one ratchet teeth are formed upon the line space wheel, then at each step-by-step movement of the latter, the platen moves through $49/1612$ of a revolution, or 10.94 degrees. This ap- 130

proximates the usual line spacing, but is an aliquant part of a complete revolution, so that at successive revolutions of the platen the lines of type impressions overlap, and 5 hence the entire surface of the platen, considered circumferentially, is evenly subjected to the blows of the types. It will further be seen that the pinion-carrying crank 22, besides serving as a stationary support 10 for the double pinion, may at any time be rotated by using the finger wheel 30. The action of the brake 31, while sufficient to hold the crank 22 stationary during ordinary rotative movements of the platen, is not so 15 powerful as to make it difficult to turn the finger wheel 30. Upon turning the crank 22 by means of said wheel, the double pinion 20, 21 is caused to rotate upon its axis 38, owing to its engagement with the line-space 20 wheel gear 17, which is held stationary by the spring check 37. This rotation of the pinion 21, which is in the nature of a planetary movement, is communicated to the pinion 20, and through the latter the gear 14 and 25 the platen are effected.

During a complete revolution of the crank 22, the double pinion is given $3 \frac{10}{13}$ revolutions about the axis 38; and at each revolution of the double pinion upon said axis, 30 the gear 14 is advanced a distance equal to the difference in the numbers of the teeth of the pinions, namely, one tooth. During an entire revolution of the crank, said gear 14 is accordingly advanced a distance equal to 35 $3 \frac{10}{13}$ teeth, this movement of the gear and platen being in the same direction as that in which the finger wheel 30 is rotated. Thus the platen may be finely adjusted while the line space wheel remains stationary, whereby 40 any desired line or point upon the paper may be brought into register with the printing line or point upon the platen, or with the usual platen scale. This adjustment may of course be effected in either direction; and 45 when the line on the paper is adjusted to the scale, either of the other finger wheels 12 and 13 may be operated to rotate the platen two notches to bring the line up to printing position as usual.

50 It will be understood that the crank 22 may be stopped at any point in its revolution, as required, and that thereafter the double pinion thereon will perform the function before described of causing the platen 55 to creep with reference to the line space wheel at the usual line spacing operation. Thus by a simple mechanism, which may be readily applied to existing machines, the two-fold object is gained of preserving the 60 smoothness of the printing surface of the platen, and enabling the latter to be adjusted irregularly when desired, and without the necessity of first releasing any clutch or the like.

65 It will be seen that the tension of the

spring 31 and hence the degree of friction produced thereby, may be adjusted by loosening the tangential screw 28 until the wheel 30 and hub 29 may be turned freely upon the threaded sleeve 27, either to increase the tension upon said friction spring or to decrease it; and that thereupon said screw 28 may be tightened, thus making the finger wheel rigid with said sleeve and hence with the crank 22. 70

The rim portion 18 of the line space wheel is provided with a continuous peripheral cam groove 39, into which projects a stud 39^a, which is threaded into the shell 15, the latter being rigid with the platen, and the stud being provided with an anti-friction roll 39^b which fits the groove. By means of this construction, the platen is slowly reciprocated endwise during its successive rotations, the endwise movements depending 85 upon the relative rotary movements between the platen and the line space wheel. The latter is laterally motionless, and it will be observed that the pinion 20 is widened, so as to remain always in mesh with the platen 90 gear 14 during its lateral movements. Thus the platen is caused to creep both circumferentially and endwise, so that every spot upon its working surface is evenly subjected to the blows of the types, whereby the type impressions are prevented from sinking deeper at 95 successive revolutions of the platen.

It will be observed that the train of gear wheels 17, 21, 20, 14 enables the line space wheel 16 to rotate the platen 1 at a different 100 rate of speed, or in other words, differentiates the movement of the platen from that of the line space wheel; that the normally stationary sleeve or supporting device 23, 26 is mounted upon the platen frame and projects 105 inwardly therefrom, extending through the line space wheel and in line with the platen axis to a point between the line space wheel and platen, at which point the double pinion 20, 21 is mounted upon the arm 22 thereon; that said train of gear wheels is arranged interiorly of the platen body, being confined 110 within an inclosure consisting of a housing or drum, whereof one side consists of the line space wheel and the other side consists of the 115 platen structure, the latter forming the periphery of the housing, and the rim 18 of the line space wheel telescoping within the platen; that the line space wheel closes one end of the hollow platen body; that said 120 gears 14—17 are arranged side by side at the platen side of the line space wheel, the gear 17 being disposed between the platen gear 14 and the line space wheel; that the line space wheel is mounted upon the supporting sleeve 125 23 between the arm 22 and the end bar 10 of the platen frame; that the double pinion 20, 21 turns upon a stationary axis 38 which is eccentric to the platen axis 8; that the line space wheel 16 has a set of coarse teeth upon 130

its periphery, and an internal set of fine teeth; that the gears 14—17 have approximately equal diameters, the diameter of the platen being greater than that of either gear 5 and approximating that of the line space wheel; and that the platen axle 8 is supported in and projects through the pinion-supporting device 23, 26, and carries at its outer end the finger wheel 13. It will also be seen 10 that the finger wheel 30 is fixed upon the cylindrical support or sleeve 26, and thereby controls the double pinion 20, 21, so that upon turning the finger wheel, a movement of the platen is effected relatively to or independently of the line space wheel; and that 15 during the movement of said finger piece and said sleeve about the platen axis, said double pinion has a planetary movement, that is, an orbital revolution about the platen axis, 20 while also rotating upon its own axis; that the devices which operate automatically for varying the lines of impression upon the platen are thus also manually adjustable, for making fine adjustments of the platen and 25 the paper thereon, both of these objects being effected by different operations of one set or train of gearing; that during the adjustment of the platen, the member 17 of said train remains stationary, being under the 30 control of the line space check 37; that means, as the brake 31, are provided for maintaining the axis 38 of the double pinion 21, 22 stationary during the ordinary operation of the line space wheel and platen; and 35 that the finger wheel 30 revolves the said double pinion bodily about the platen axis. It will also be seen that means are arranged interiorly of the platen body for effecting automatic endwise reciprocations of the 40 platen.

Referring now to Figs. 9 to 21 inclusive, it will be seen that in this form of the invention a single wide pinion 40, having eighteen teeth, is journaled upon an eccentric 41, provided upon the end of a sleeve 42, to which is secured by a set screw 43 the hub of a finger wheel 30^a. The eccentric, whose function corresponds with that of the crank 22 at Fig. 3, is provided with a flange 44 and the pinion 50 40 is confined between said flange and a flange 45 formed upon a collar 46 mounted upon the sleeve 42. At its opposite side or end the collar abuts against a washer 47 which is placed against the inner side of the 55 platen frame, and is also reduced at 46^a to form a bearing for a series of bearing rollers 24^a, supporting the line space wheel, and confined between the washer 47 and the unreduced portion of the collar 46. A split friction washer 48 is inserted between the inner 60 end of the hub of wheel 30^a and the outer side of the platen frame, whereby accidental rotary movements of the eccentric 41 are prevented. The internal gear 14^a, which is 65 attached to the shell 15^a by means of screws

49, is provided with twenty-two teeth, while the internal gear 17^a, which is attached by screws 17^b to the edge of the rim portion of the line space wheel, is provided with twenty-one teeth, so that during its ordinary paper-feeding movements the velocity of the platen is less than that of the line space wheel to the extent represented by one tooth of the pinion 40. Moreover, by rotating the thumb wheel 30^a the platen may be irregularly 70 finely adjusted, the eccentric 41 effecting the same planetary movement of the pinion 40 as is given the pinions 20 and 21 by the crank 22. A friction spring or brake 50 is inserted in a notch 51 (Figs. 12 and 14) formed in the rim portion of the line space wheel, whereby accidental rotative movements or back-lash of the platen relatively to the line space wheel may be prevented, although if the parts are well fitted, this brake may be omitted. 75

Other variations may be made within the scope of my invention, and portions of my improvements may be used without others, as for instance, the brake 31 may be omitted, 80 permitting the double pinion 20—21 to revolve with the platen and line-space wheel, thus retaining the use of the finger wheel 30 for adjusting the platen, but discarding the differentiation of the platen movement from that of the line space wheel; or, if desired, 85 the finger wheel 30 may be omitted, and the sleeve or support 26, 22 made fast to the platen frame, thus retaining the advantage of differentiating the movement of the platen from that of the line space wheel but discarding the independent adjustment of the platen; or the cam 39 and stud 41 may either be 90 omitted, or used in connection with other devices, retaining the advantage of confining said cam and stud within the platen body. 95

While I prefer to employ internal gears as illustrated, still spur or other gears may be used for certain features of my improvements.

What I claim as new and desire to secure by Letters Patent, is:—

1. In a typewriting machine, the combination with a line space wheel and a platen, of a train of gear wheels arranged interiorly of the platen body and enabling the line space wheel to rotate the platen at a different rate of speed.

2. In a typewriting machine, the combination with a platen frame, a cylindrical platen and a concentric line space wheel, of a device upon said platen frame extending to a point between said line space wheel and said platen, a pinion mounted upon said device, a gear wheel connected to said pinion and also to the line space wheel, and a second gear wheel connected to the pinion and also to the platen, said pinion and gear wheels differentiating the movement of the platen from that of the line space wheel.

3. In a typewriting machine, the combination of a platen frame, a platen, a line space

70

wheel concentric with and arranged at one end of the latter, and mechanism carried partly by said line space wheel and operating to differentiate the movement of the platen 5 from the line space wheel; said mechanism being confined within a housing or drum whereof one side consists of the line space wheel and the other side consists of the platen, and one of said line space wheel 10 and platen elements forming at least a portion of the periphery of said housing.

4. In a typewriting machine, the combination with a platen frame, a platen and a line space wheel at one end of the latter, of a 15 supporting device carried by said platen frame and extending through said line space wheel, a pinion mounted upon said supporting device, a wheel connected to said pinion and also to the line space wheel, and a wheel 20 also connected to said pinion and to the platen; said wheels and pinion differentiating the movement of the platen from that of the line space wheel.

5. In a typewriting machine, the combination with a platen frame, a platen and a line 25 space wheel at one end of the latter, of a supporting device carried by said platen frame and extending through said line space wheel; a pinion mounted upon said supporting device; a wheel connected to said pinion and also to the line space wheel; a wheel also 30 connected to said pinion and to the platen; said wheels and pinion differentiating the movement of the platen from that of the line space wheel; and a platen axle projecting 35 through said supporting device and carrying at its outer end a finger wheel.

6. In a typewriting machine, the combination with a platen frame, a platen and a line 40 space wheel, of a supporting device mounted at one end upon the platen frame and projecting inwardly therefrom in line with the platen axis; a pinion mounted upon said supporting device; a wheel connected to 45 said pinion and also to the line space wheel; a wheel also connected to said pinion and to the platen; said wheels and pinion differentiating the movement of the platen from that of the line space wheel; and a platen shaft 50 mounted at one end in the platen frame and at the other end supported in said inwardly projecting device.

7. In a typewriting machine, the combination with a platen frame, a platen and a 55 line space wheel, of a supporting device mounted at one end upon the platen frame and projecting inwardly therefrom in line with the platen axis; a pinion mounted upon the inner end of said supporting device; a 60 wheel connected to said pinion and also to the line space wheel; a wheel also connected to said pinion and to the platen; said wheels and pinion differentiating the movement of the platen from that of the line space wheel; and a platen shaft 65 extending at one end

through the platen frame and carrying a finger wheel at its outer end, and extending at the other end through said inwardly projecting device and also carrying a finger wheel at said other end.

8. In a typewriting machine, the combination with a platen frame, a hollow cylindrical platen, and a line space wheel closing one end of the platen and concentric therewith, of mechanism arranged within the inclosure 70 formed by the platen and line space wheel for differentiating the movement of the platen from that of the line space wheel; said differentiating mechanism having a stationary connection to the platen frame.

9. In a typewriting machine, the combination with a platen frame, a hollow cylindrical platen, and a line space wheel closing one end of the platen and concentric therewith, of mechanism arranged within the inclosure 75 formed by the platen and line space wheel and including a wheel turning upon a stationary axis which is eccentric to the platen axis, for differentiating the movement of the platen from that of the line space wheel.

10. In a typewriting machine, the combination with a platen of a line space wheel having internally arranged teeth, a platen having a gear, and a pinion connected to both 80 said line space teeth and said platen gear and differentiating the movement of the platen from that of the line space wheel.

11. In a typewriting machine, the combination with a platen of a line space wheel having internally arranged teeth, a platen 85 having an internal gear, and a pinion connected to both said line space teeth and said platen gear and differentiating the movement of the platen from that of the line space wheel.

12. In a typewriting machine, the combination with a platen and a line space wheel having two sets of teeth, one of which is internal, of a spring check engaging one of said 90 sets of teeth, a pinion engaging the other of said sets of teeth, and a gear wheel connected to said pinion and also to said platen in such a manner as to differentiate the movement of said platen from that of said line space wheel.

13. In a typewriting machine, the combination with a platen of a line space wheel having two sets of teeth, whereof the teeth in one set are coarse and in the other set are fine, and said set of fine teeth forming an internal gear, means for operating said coarse 100 set of teeth, a pinion engaging said fine set of teeth, and an internal gear connected to said platen and also to said pinion, and differentiating the movement of the platen from that of the line space wheel.

14. In a typewriting machine, the combination of two internal gears of approximately equal diameters; a toothed device operatively connecting said gears and differentiating their movements; a platen connected to 110 115 120 125 130

one of said gears, and a line space wheel connected to the other of said gears; the diameter of said platen being greater than the diameter of the gear which is connected thereto.

15. In a typewriting machine, the combination of two internal gears of approximately equal diameters; a toothed device operatively connecting said gears and differentiating their movements, a platen connected to one of said gears, and a line space wheel connected to the other of said gears; the diameter of said platen being greater than the diameter of said gear which is connected thereto, and said line space wheel having external or peripheral teeth and being of approximately the same diameter as the platen.

16. In a typewriting machine, the combination with a platen and a line space wheel at the end thereof, of two internal gears having unequal numbers of teeth and arranged side by side, and a rotatory toothed member having a stationary axis and in engagement with both of said internal gears; one of the latter being fast to the platen and the other being fast to the line space wheel.

17. In a typewriting machine, the combination with a platen and a line space wheel at the end thereof, of two internal gears having unequal numbers of teeth and arranged side by side at the platen side of said line space wheel, and a rotary toothed member having a stationary axis and in engagement with both of said internal gears; one of the latter being fast to the platen and the other being fast to the line space wheel.

18. In a typewriting machine, the combination with a cylindrical platen and a line space wheel concentric therewith, of two internal gears having unequal numbers of teeth, one fast to the platen and the other fast to the line space wheel, and a toothed device rotating upon a stationary axis eccentric to the platen axis and engaging both of said internal gears.

19. In a typewriting machine, the combination with a cylindrical platen and a line space wheel concentric therewith, of two internal gears, one fast to the platen and the other fast to the line space wheel, and a toothed device rotating upon a stationary axis eccentric to the platen axis and engaging both of said internal gears and differentiating the rotary movement of said platen from that of said line space wheel.

20. In a typewriting machine, the combination with a line space wheel and a cylindrical platen of a train of gearing arranged interiorly of the platen body and connecting the platen to said line space wheel and enabling the latter to rotate the platen at a rate of speed different from its own; said train of gearing including at least one internal gear wheel connected to one of said

platen and line-space-wheel elements, a pinion engaging said internal gear wheel, and a gear wheel connected to said pinion and also to the other of said platen and line-space-wheel elements.

21. In a typewriting machine, the combination with a line space wheel and a cylindrical platen of a train of gearing arranged interiorly of the platen body and enabling the line space wheel to rotate the platen at a rate of speed different from its own; said train including a pair of internal gears arranged side by side and a toothed device rotating upon a fixed axis eccentric to the platen axis and engaging both of said internal gears.

22. In a typewriting machine, the combination with a line space wheel and a cylindrical platen of a train of gearing arranged interiorly of the platen body and enabling the line space wheel to rotate the platen at a different rate of speed, said train including a pair of internal gears arranged side by side and having unequal numbers of teeth, and a toothed device rotating upon a fixed axis eccentric to the platen axis and engaging both of said internal gears.

23. In a typewriting machine, the combination with a platen frame, a cylindrical platen and a line space wheel concentric with said platen, of a device upon said platen frame extending to a point between said line space wheel and said platen, a pinion mounted upon said device, an internal gear wheel connected to said pinion and also to the line space wheel, and a second internal gear wheel connected to the pinion and also to the platen, said pinion and gear wheels differentiating the movement of the platen from that of the line space wheel.

24. In a typewriting machine, the combination with a platen frame, a cylindrical platen, and a line space wheel concentric with and arranged at one end of the latter, of mechanism carried partly by said line space wheel and operating to differentiate the movement of the platen from that of the line space wheel; said mechanism being confined within a housing or drum whereof one side consists of the line space wheel and the other side consists of the platen, and one of said line space wheel and platen elements having at least a portion of the periphery of said housing; said differentiating mechanism including a pair of internal gear wheels and a single toothed device engaging both thereof, and one of said gear wheels being fast to the platen and the other fast to the line space wheel.

25. In a typewriting machine, the combination with a platen frame, a platen and a line space wheel at one end of the latter, of a supporting device carried by said platen frame and extending through said line space wheel; a pinion mounted upon said sup-

porting device; an internal gear wheel connected to said pinion and also to the line space wheel; and an internal gear wheel also connected to said pinion and to the platen; 5 said internal gear wheels and pinion differentiating the movement of the platen from that of the line space wheel.

26. In a typewriting machine, the combination with a platen of a gear wheel connected thereto; a rotary toothed device engaging said gear wheel; one of said gear-wheel and toothed-device elements having greater diameter than and surrounding the other, a companion gear wheel for said gear wheel; said toothed device also engaging said companion gear wheel; and a line space wheel connected to said companion gear wheel; said gear wheels and said toothed device coöperating to differentiate the rotary 20 movement of said platen from that of said line space wheel.

27. In a typewriting machine, the combination with a platen frame, a platen and a line space wheel at one end of the latter, of 25 a supporting device carried by said platen frame and extending through said line space wheel; a pinion mounted upon said supporting device; an internal gear wheel connected to said pinion and also to the line 30 space wheel; and an internal gear wheel also connected to said pinion and to the platen; said internal gear wheels and pinion differentiating the movement of the platen from that of the line space wheel; and a platen 35 shaft projecting through said supporting device and carrying at its outer end a finger wheel.

28. In a typewriting machine, the combination with a platen frame, a platen and a 40 line space wheel, of a supporting device mounted at one end upon the platen frame and projecting inwardly therefrom in line with the platen axis; a pinion mounted upon said supporting device; an internal gear 45 wheel connected to said pinion and also to the line space wheel; an internal gear wheel also connected to said pinion and to the platen, said internal gear wheels and pinion differentiating the movement of the platen 5 from that of the line space wheel; and a platen axle shaft mounted at one end in the platen frame and at the other end supported in said inwardly projecting device.

29. In a typewriting machine, the combination with a platen frame, a platen and a 55 line space wheel, of a supporting device mounted at one end upon the platen frame and projecting inwardly therefrom, a pinion mounted upon said supporting device; an 60 internal gear wheel connected to said pinion and also to the line space wheel; an internal gear wheel also connected to said pinion and to the platen; said internal gear wheels and pinion differentiating the movement of the 65 platen from that of the line space wheel;

and a platen shaft projecting at one end through the platen frame, and projecting at the other end through said inwardly projecting device, and also carrying at each end a finger wheel.

70

30. In a typewriting machine, the combination with a platen frame, a hollow cylindrical platen, and a line space wheel closing one end of the platen, of mechanism arranged within the inclosure formed by the platen 75 and line space wheel for differentiating the movement of the platen from that of the line space wheel; said mechanism including a pair of internal gears and a single device rotating upon a stationary axis eccentric to 80 the platen axis and engaging both of said internal gears.

31. In a typewriting machine, the combination with a platen frame, a platen and a line space wheel, of a pair of internal gear 85 wheels concentric with the platen and line space wheel, a stationary support carried by the platen frame, and a toothed device mounted upon said stationary support to turn upon an axis eccentric to the platen axis, 90 said toothed device engaging both of said internal gears; one of the latter being fast to the platen and the other thereof being connected to the line space wheel, and one of said internal gears having more teeth than 95 the other thereof.

32. In a typewriting machine, the combination with a platen frame, a platen and a line space wheel, of a pair of internal gear wheels mounted concentric with the platen 100 and line space wheel, a stationary support carried by the platen frame; and a toothed device mounted upon said stationary support to turn upon an axis eccentric to the platen axis, said toothed device engaging 105 both of said internal gears; one of the latter being fast to the platen and the other thereof being connected to the line space wheel; one of said internal gears having more teeth than the other thereof, and said support being 110 mounted at one end upon the platen frame and extending axially of the platen to the interior thereof, and carrying said toothed device upon its inner end.

33. In a typewriting machine, the combination with a platen frame, a cylindrical platen and a concentric line space wheel at one end thereof, of an internal gear arranged within the platen and secured thereto; a companion internal gear arranged between 115 the first internal gear and the line space wheel and fast to the latter; a support projecting from said platen frame through said line space wheel, and a toothed device mounted to turn upon said support upon an 120 axis eccentric to said platen and engaging both of said internal gears and causing differential movement of the latter.

34. In a typewriting machine, the combination with a platen frame, a cylindrical 125

axis eccentric to said platen and engaging both of said internal gears and causing differential movement of the latter.

platen and a concentric line space wheel at one end thereof, of an internal gear arranged within the platen and secured thereto; a companion internal gear arranged between 5 the first internal gear and the line space wheel and fast to the latter; a support projecting from said platen frame through said line space wheel; an arm upon said support; a toothed device mounted to turn upon said 10 arm eccentrically to said platen and engaging both of said internal gears and causing differential movement of the latter; and a platen axle mounted at one end upon the platen frame and at the other end upon said 15 internally projecting support.

35. In a typewriting machine, the combination with a platen frame, a cylindrical platen and a concentric line space wheel at one end thereof, of an internal gear arranged 20 within the platen and secured thereto; a companion internal gear arranged between the first internal gear and the line space wheel and fast to the latter; a support projecting from said platen frame through said 25 line space wheel; the latter being journaled upon said support, and a toothed device mounted eccentrically upon said support and engaging both of said internal gears and causing differential movement of the latter.

30. 36. In a typewriting machine, the combination with a platen frame, a cylindrical platen and a concentric line space wheel at one end thereof, of an internal gear arranged within the platen and secured thereto; a 35 companion internal gear arranged between the first internal gear and the line space wheel and fast to the latter; a cylindrical supporting device projecting from said platen frame through said line space wheel; a toothed device mounted to turn upon said 40 support upon an axis eccentric to said platen and engaging both of said internal gears and causing differential movement of the latter; and bearing rollers interposed between said 45 line space wheel and said supporting device.

37. In a typewriting machine, the combination with a platen frame having end bars, a cylindrical platen, and a concentric line space wheel, of a hollow support or sleeve projecting inwardly from one of said end bars; an arm upon the inner end of said support; a toothed device pivoted upon the end of said arm; a pair of internal gears meshing with said toothed device and differentiated in 55 speed thereby; one of said internal gears being within the platen body and fast thereto, the other thereof being fast to the line space wheel, and the latter being disposed upon said hollow support between said arm and 60 said end bar; a platen axle mounted at one end in the opposite end bar and projecting through said hollow support; and a finger wheel fixed upon the projecting end of said axle.

65. 38. In a typewriting machine, the com-

bination with a platen, a platen axle, and a line space wheel, of a gear connected to the platen, a gear connected to the line space wheel, all of said elements being concentrically arranged and said gears having unequal numbers of teeth; a planet wheel connecting said gears; a device revoluble about the platen axis and carrying said planet wheel, and also provided with a finger wheel; and a finger wheel connected to the 75 platen axle at each end thereof.

39. In a typewriting machine, the combination with a line space wheel and a cylindrical platen, of a train of gear wheels arranged interiorly of the platen body and 80 connecting the platen to said line space wheel; and a finger wheel concentric with the platen axis and connected to one member of said train said line space wheel being disposed between said platen and said finger 85 wheel and the movement of said member by said finger wheel effecting an adjustment of the platen independently of the line space wheel.

40. In a typewriting machine, the combination with a line space wheel and a cylindrical platen, of two gears, one fast to the platen and the other fast to the line space wheel; said gears being concentric with and confined by the line space wheel and 95 platen; a planet wheel connecting said gears; a device carrying said planet wheel and revoluble about the platen axis; and a finger piece mounted upon said device outside of the platen; the movement of said planet 100 wheel by said finger piece causing the platen to rotate relatively to the line space wheel.

41. In a typewriting machine, the combination with a platen frame, a cylindrical platen and a line space wheel concentric with 105 said platen, of a device upon said platen frame extending to a point between said line space wheel and the platen; said device being revoluble about the axis of the platen; a pinion carried by said device; a gear wheel 110 connected to said pinion and also to the line space wheel; a second gear wheel connected to the pinion and also to the platen; and a finger wheel fixed upon said pinion-carrying device; the movement of said pinion by 115 means of said finger wheel effecting a movement of the platen independently of the line space wheel.

42. In a typewriting machine, the combination with a platen frame, a platen and 120 a line space wheel at one end of the latter, of a supporting device carried by said platen frame and extending through said line space wheel; said device being revoluble about the platen axis; a pinion mounted upon said 125 supporting device; a wheel connected to said pinion and also to the line space wheel; a wheel also connected to said pinion and to the platen; and a finger wheel fixed upon said pinion-carrying device at a point out- 130

side of said platen frame; the movement of said pinion by means of said finger wheel effecting a movement of the platen independently of the line space wheel.

5 43. In a typewriting machine, the combination of a line space wheel having internally arranged teeth, a platen having a gear concentric with said line space wheel; a planet wheel connecting said line space

10 wheel to said gear; and a finger wheel connected to said planet wheel; the movement of the latter effected by said finger wheel causing the platen to rotate while the line space wheel is stationary.

15 44. In a typewriting machine, the combination of a line space wheel having internally arranged teeth; a platen having an internal gear concentric with said line space wheel; a planet wheel connecting said line

20 space wheel to said gear; and a finger wheel connected to said planet wheel; the movement of the latter effected by said finger wheel causing the platen to rotate while the line space wheel is stationary.

25 45. In a typewriting machine, the combination with a platen, of a line space wheel having two sets of teeth, one of which is internal; a spring check engaging one of said sets of teeth; a pinion engaging the 30 other of said sets of teeth; a gear wheel connected to said pinion and also to said platen; a revolute device carrying said pinion; and a finger wheel upon said revolute device; the movement of said pinion effected by 35 said revolute device causing the platen to rotate independently of the line space wheel.

40 46. In a typewriting machine, the combination with a platen of a line space wheel having two sets of teeth, whereof the teeth in one set are coarse and those in the other set are fine, said set of fine teeth forming an internal gear; means for operating said line space wheel; a pinion engaging said fine set of teeth; an internal gear connected to said 45 platen and also to said pinion; and a device carrying said pinion and revolute concentrically with the platen for effecting a movement of the latter independently of the line space wheel.

50 47. In a typewriting machine, the combination with a platen and a line space wheel at the end thereof, of two internal gears having unequal numbers of teeth and arranged side by side; a rotatory toothed member in engagement with both of said internal gears; one of the latter being fast to the platen and the other being fast to the line space wheel; and a manually revolute device carrying said toothed member.

60 48. In a typewriting machine, the combination with a platen and a line space wheel at the end thereof, of two internal gears having unequal numbers of teeth and arranged side by side at the platen side of said 65 line space wheel; a rotatory toothed member

in engagement with both of said internal gears; one of the latter being fast to the platen and the other being fast to the line space wheel; and a manually revolute device upon which said toothed member is eccentrically mounted.

70 49. In a typewriting machine, the combination with a cylindrical platen and a line space wheel concentric therewith, of two internal gears having unequal numbers of teeth, one fast to the platen and the other fast to the line space wheel; a toothed device mounted eccentrically to the platen axis and engaging both of said internal gears, and a device revolute concentrically with the 75 platen and carrying said toothed device and also provided with a finger piece.

80 50. In a typewriting machine, the combination with a line space wheel and a cylindrical platen, of a train of gear wheels arranged interiorly of the platen body and connecting the platen to said line space wheel; said train of gear wheels including at least one internal gear wheel connected to one of said platen and line-space-wheel elements, a pinion engaging said internal gear wheel, and a gear wheel connected to said pinion and also to the other of said platen and line-space-wheel elements; and a device carrying said pinion and revolute concentrically with said gear wheels, said revolute device being provided with a finger wheel, and the movement of said pinion effected thereby causing a movement of the platen 85 independently of the line space wheel.

90 51. In a typewriting machine, the combination with a line space wheel and a cylindrical platen of a train of gear wheels arranged interiorly of the platen body; the said train including a pair of internal gears 95 arranged side by side, a toothed device rotating upon an axis eccentric to the platen axis and engaging both of said internal gears, and the latter having unequal numbers of teeth; and a device carrying said pinion and revolute concentrically with said gear wheels, said revolute device being provided with a finger wheel, and the movement of said pinion effected thereby causing a movement of the platen 100 independently of the line space wheel.

105 52. In a typewriting machine, the combination with a platen frame, a cylindrical platen and a line space wheel concentric with said platen, of a device upon said platen frame extending to a point between said line space wheel and said platen; a pinion mounted upon said device; an internal gear wheel connected to said pinion and also to the line space wheel; and a second internal 110 gear wheel connected to the pinion and also to the platen; said device being revolute concentrically with said platen and being provided with a finger wheel, and the movement of said pinion by means of said device 115

120 125 130

125 53. In a typewriting machine, the combination with a platen frame, a cylindrical platen and a line space wheel concentric with said platen, of a device upon said platen frame extending to a point between said line space wheel and said platen; a pinion mounted upon said device; an internal gear wheel connected to said pinion and also to the line space wheel; and a second internal gear wheel connected to the pinion and also to the platen; said device being revolute concentrically with said platen and being provided with a finger wheel, and the movement of said pinion by means of said device 130

effecting a rotation of the platen while the line space wheel remains stationary.

53. In a typewriting machine, the combination with a platen frame, a platen and a line space wheel, of a pair of internal gear wheels concentric with the platen and line space wheel; a toothed device mounted to turn upon an axis eccentric to the platen axis, said toothed device engaging both of said internal gears; one of the latter being fast to the platen and the other thereof being connected to the line space wheel, and one of said internal gears having more teeth than the other thereof; said support being revolu- 15 bly mounted at one end upon the platen frame and extending axially of the platen to the interior thereof, and carrying said toothed device upon its inner end, and a finger piece being mounted upon said support 20 without said platen frame.

54. In a typewriting machine, the combination with a platen of automatically operating devices for varying the lines of impression upon the platen; said automatically operating devices being also manually adjustable for making fine adjustments of the platen and the paper thereon.

55. In a typewriting machine, the combination with a platen and its line space lever 30 of mechanism for turning the platen through an aliquant part of a complete revolution at each actuation of the line space lever; said mechanism including members whereof one may remain stationary while others are 35 moved at will for making fine adjustments of the platen and the paper thereon.

56. In a typewriting machine, the combination with a platen and a line space wheel having evenly spaced teeth, of means intervening between the line space wheel and the platen for causing the latter to turn through an aliquant portion of a complete revolution while the line space wheel turns through an aliquot portion of a complete revolution; 45 said intervening means being also movable while the line space wheel remains stationary for making fine adjustments of the platen and the paper thereon.

57. In a typewriting machine, the combination with a platen and a line space wheel, of a train of gearing connecting the line space wheel to the platen; the several members of said train coöperating to differentiate the movement of the platen from that of the line 50 space wheel, and a portion of said train being movable independently of the line space wheel for effecting adjustments of the platen and the paper thereon while the line space wheel remains at rest.

60 58. In a typewriting machine, the combination with a platen and a line space wheel, of a check for said line space wheel; and a train of gearing connecting the line space wheel to the platen; the several members of 65 said train coöperating to differentiate the

movement of the platen from that of the line space wheel when the latter is moved, and said gearing being also operable while the line space wheel remains under the control of said check, for effecting independent rotation of the platen.

59. In a typewriting machine, the combination with a platen and a line space wheel, of a gear wheel connected to the platen, a gear wheel connected to the line space wheel, and a toothed device connecting said gear wheels and operating to differentiate the movement of the platen from that of the line space wheel; said toothed connecting device being also operable while the line space wheel remains stationary, for effecting independent adjustments of the platen.

60. In a typewriting machine, the combination with a platen of a line space wheel having a set of teeth, a set of teeth on the platen, and a pinion connected to both of said sets of teeth and differentiating the movement of the platen from that of the line space wheel; said pinion being also movable while the line space wheel remains stationary for making fine adjustments of the platen and the paper thereon.

61. In a typewriting machine, the combination with a platen and a line space wheel, of a gear connected to the platen; a concentric gear connected to the line space wheel; a pinion or toothed device meshing with said gears and movable independently of said gears about the axis of the latter; means for maintaining the axis of said pinion in a fixed position during the usual movements of the line space wheel and platen; said pinion and gears differentiating the movement of the platen from that of the line space wheel; and means operable at will for revolving said pinion about the axis of said gears.

62. In a typewriting machine, the combination with a platen frame of a platen mounted thereon; a line space wheel concentric with said platen; and means for both automatically differentiating the movement of the platen from that of the line space wheel and also rotating the platen independently of the line space wheel at will; said means including both a rotary device mounted upon the platen frame and connected to the line space wheel and to the platen, and a finger piece connected to said rotary device for revolving it bodily about the platen axis.

63. In a typewriting machine, the combination of a platen frame; a platen, a line space wheel concentric with the platen; a toothed wheel secured to the platen; a companion toothed wheel rigid with the line space wheel; a pinion mounted eccentrically upon a device which is rotatable about the platen axis; means for holding said device stationary during the usual movements of the platen and line space wheel; said pinion and gears differentiating the movement of

the platen from that of the line space wheel; and a finger piece mounted upon said device for revolving the pinion bodily about the platen axis.

5 64. In a typewriting machine, the combination with a platen and a line space wheel, of a gear connected to the platen; a gear connected to the line space wheel; a toothed device connecting said gears; a finger wheel 10 controlling said toothed device; and a friction device for holding said finger wheel stationary during the usual movements of the line space wheel and platen; said gears differentiating the movement of the platen 15 from that of the line space wheel, and the construction and arrangement being such that upon turning said finger wheel, a movement of one of said platen and line space wheel elements is effected relatively to the 20 other.

65. In a typewriting machine, the combination with a platen and a line space wheel, of a check for said line space wheel; a gear connected to the platen; a gear connected to 25 the line space wheel; a toothed device connecting said gears; and a finger wheel controlling said toothed device; said finger wheel being stationary during the ordinary movement of the line space wheel, and said gears 30 differentiating the movement of the platen from that of the line space wheel, and the construction and arrangement being such that upon turning said finger wheel, a movement of said platen is effected while said line 35 space wheel is held stationary by said check.

66. In a typewriting machine, the combination of a platen; a line space wheel; a gear wheel connected to the platen; a gear wheel connected to the line space wheel; said gears, 40 line space wheel and platen being concentrically arranged; a planet wheel connecting said gears; a finger piece connected to said planet wheel for revolving the same about the platen axis, such movement of the planet 45 wheel effecting a rotary movement of the platen independently of the line space wheel; and a friction device constantly opposing movement of said planet wheel about the platen axis, whereby the said planet wheel 50 is held against movement around the platen axis during the movement of the line space wheel.

67. In a typewriting machine, the combination with a platen and a concentric line 55 space wheel, of a train of gearing connecting the line space wheel to the platen; said train including a gear rigid with the platen, a gear rigid with the line space wheel, and a planet wheel connecting said gears; and a device 60 whereon said planet wheel is pivoted, said device being revoluble about the platen axis; a finger piece mounted upon said revoluble device; and a friction device which prevents 65 revolution of said device during the ordinary operation of the line space wheel.

68. In a typewriting machine, the combination with a platen of a line space wheel; a pair of gears one connected to the platen and the other to the line space wheel, said gears having slightly different numbers of teeth; a 70 planet wheel connecting said gears; a finger wheel for operating said planet wheel to cause the platen to rotate independently of the line space wheel; and a device holding said finger wheel stationary during the ordinary 75 operation of the line space wheel and platen.

69. In a typewriting machine, the combination with a line space wheel and a cylindrical platen, of a train of gear wheels arranged interiorly of the platen body and 80 connecting the platen to said line space wheel; a finger wheel concentric with the platen axis and connected to one member of said train; said line space wheel being disposed between said platen and said finger 85 wheel, and the movement of said member by said finger wheel effecting an adjustment of the platen independently of the line space wheel; and a device constantly opposing the revolution of said finger wheel. 90

70. In a typewriting machine, the combination with a platen frame, a cylindrical platen and a line space wheel concentric with said platen, of a device upon said platen frame extending to a point between said line 95 space wheel and the platen; said device being revoluble about the axis of the platen; a pinion carried by said device; a gear wheel connected to said pinion and also to the line space wheel; a second gear wheel connected 100 to the pinion and also to the platen; a finger wheel fixed upon said pinion-carrying device; the movement of said pinion by means of said finger wheel effecting a movement of the platen independently of the line space 105 wheel; and a brake between said revoluble device and said platen frame.

71. In a typewriting machine, the combination with a platen frame, a platen and a line space wheel at one end of the latter, of a 110 supporting device carried by said platen frame and extending through said line space wheel, said device being revoluble about the platen axis; a pinion mounted upon said revoluble device; a wheel connected to said 115 pinion and also to the line space wheel; a wheel also connected to said pinion and to the platen; a finger wheel fixed upon said pinion-carrying revoluble device at a point outside of said platen frame; the movement 120 of said pinion caused by said finger wheel effecting a movement of the platen independently of the line space wheel; and a friction washer between said platen frame and said finger wheel, for holding the latter stationary 125 during the ordinary movement of the line space wheel and platen.

72. In a typewriting machine, the combination of a line space wheel having internal teeth; a platen having an internal gear con- 130

centric with said line space wheel; a planet wheel connecting said line space wheel to said gear; a finger wheel connected to said planet wheel; the movement of the latter effected by said finger wheel causing the platen to rotate while the line space wheel is stationary; and means for preventing movement of the finger wheel during the ordinary operation of the line space wheel.

10 73. In a typewriting machine, the combination with a platen and a line space wheel at the end thereof, of two internal gears having unequal numbers of teeth and arranged side by side; a rotatory toothed member in 15 engagement with both of said internal gears; one of the latter being fast to the platen and the other being fast to the line space wheel; a manually revoluble device carrying said toothed member; and means for preventing 20 revolution of said revoluble device during the ordinary operation of the line space wheel.

74. In a typewriting machine, the combination with a line space wheel and a cylindrical platen of a train of gear wheels arranged interiorly of the platen body; said train including a pair of internal gears arranged side by side and a toothed device rotating upon an axis eccentric to the platen 30 axis and engaging both of said internal gears; the latter having unequal numbers of teeth; a device carrying said pinion and revoluble concentrically with said gear wheels; said revoluble device being provided with a finger 35 wheel, and the movement of said pinion effected thereby causing a movement of the platen independently of the line space wheel; and means for holding said revoluble device stationary.

40 75. In a typewriting machine, the combination of a platen frame; a platen; a platen axle; a sleeve loosely surrounding said platen axle, said sleeve being revolubly mounted in said platen frame; an arm upon said sleeve; a 45 pinion or toothed device carried by said arm; companion internal gears meshing with said toothed device, one of said gears being attached to the platen; a line space wheel to which the other of said gears is attached, 50 said line space wheel surrounding said sleeve; and a finger wheel secured upon said sleeve without the platen frame.

76. In a typewriting machine, the combination of a platen frame; a platen; a platen 55 axle; a sleeve loosely surrounding said platen axle, said sleeve being revolubly mounted in said platen frame; a pinion or toothed device carried eccentrically by said sleeve; companion internal gears meshing with said toothed device, one of said gears being attached to the platen, a line space wheel to 60 which the other of said gears is attached; said line space wheel surrounding said sleeve; a finger wheel secured upon said sleeve without 65 the platen frame; a friction device be-

tween said platen frame and said sleeve or finger wheel, said gears and toothed device differentiating the movement of the platen from that of the line space wheel; and a finger wheel upon an end of said platen axle 70 which projects through said sleeve.

77. In a typewriting machine, the combination of a platen frame; a platen; a platen axle; a sleeve loosely surrounding said platen axle, said sleeve being revolubly mounted in 75 said platen frame; a pinion or toothed device carried eccentrically by said sleeve; companion internal gears meshing with said toothed device; one of said gears being attached to the platen; a line space wheel to 80 which the other gear is attached; said line space wheel surrounding said sleeve; anti-friction rolls interposed between said line space wheel and said sleeve; a spring check engaging said line space wheel; and a finger 85 wheel secured upon said sleeve without the platen frame.

78. In a typewriting machine, the combination of a platen frame; a platen; a platen axle; a sleeve upon said platen axle; said 90 sleeve being revolubly mounted in said platen frame; a pinion or toothed device carried eccentrically by said sleeve; companion internal gears meshing with said toothed device, one of said gears being attached to the platen; a line space wheel to 95 which the other gear is attached; said line space wheel being loosely mounted upon said sleeve; a finger wheel secured upon said sleeve without the platen frame; a friction washer between said platen frame and said sleeve or finger wheel; and means for adjusting said friction washer.

79. In a typewriting machine, the combination of a platen frame; a platen; a platen axle, a sleeve upon said platen axle, said 100 sleeve being revolubly mounted in said platen frame; a pinion or toothed device carried eccentrically by said sleeve; companion internal gears meshing with said toothed device, one of said gears being attached to the 105 platen; a line space wheel with which the other gear is connected; said line space wheel surrounding said sleeve; said sleeve being threaded at an end thereof which projects from said platen frame, and said finger 110 wheel being screwed upon said threaded portion; a friction washer between said wheel and said platen frame, the tension of said washer being adjusted by the movement of said wheel along said sleeve; and means for 115 clamping said wheel upon said sleeve.

80. In a typewriting machine, the combination of a platen; a line space wheel; a gear wheel connected to the platen; a concentric gear wheel connected to the line space wheel, one of said gear wheels having one more tooth than the other; a double pinion; one member of said double pinion having one more tooth than the other member, and one of said members meshing with one of said 120 125 130

gears and the other member with the other of said gears; and hand operating means for effecting a planetary movement of said double pinion.

5. 81. In a typewriting machine, the combination of a platen; a line space wheel; a gear wheel connected to the platen; a concentric gear wheel connected to the line space wheel, one of said gear wheels having one more tooth 10 than the other; a pinion meshing with said gears; means for supporting said pinion; means for turning said support upon the axis of said platen; and means for holding said support stationary during the ordinary operation of the line space wheel.

20 82. In a typewriting machine, the combination of a platen; a line space wheel; an internal gear wheel connected to the platen; an internal concentric gear wheel connected to the line space wheel; one of said wheels having one more tooth than the other; a double pinion one of whose sets of teeth meshes with one of said gears and the other whereof meshes with the other of said gears; and 25 means for supporting said double pinion.

30 83. In a typewriting machine, the combination of a platen, a line space wheel; a gear connected to the platen; a gear connected to the line space wheel; one of said gears having more teeth and being of larger diameter than the other; a double pinion comprising large and small members, the larger member having more teeth than the smaller and meshing with the smaller of said gears; and means 35 for effecting a planetary movement of said double pinion.

40 84. In a typewriting machine, the combination of a platen; a line space wheel; an internal gear connected to the platen; an internal gear connected to the line space wheel; one of said gears having more teeth and being of larger diameter than the other; a double pinion comprising large and small members, the larger member having more 45 teeth than the smaller and meshing with the smaller of said gears; and means for effecting a planetary movement of said double pinion about the axis of said internal gears.

50 85. In a typewriting machine, the combination with a line space wheel and a platen, of a train of gear wheels arranged interiorly of the platen body and enabling the line space wheel to rotate the platen at a different rate of speed, and means also arranged interiorly of the platen body for effecting automatically endwise reciprocations of the platen.

60 86. In a typewriting machine, the combination with a platen frame, a cylindrical platen and a concentric line space wheel, of a device upon said platen frame extending to a point between said line space wheel and said platen; a pinion mounted upon said device; a gear wheel connected to said pinion 65 and also to the line space wheel; and a second

gear wheel connected to the pinion and also to the platen; said pinion and gear wheels differentiating the movement of the platen from that of the line space wheel, and one of said line-space-wheel and platen elements 70 having a cam and the other having a device for engaging said cam, for effecting endwise reciprocations of the platen.

75 87. In a typewriting machine, the combination with a platen frame, a platen, and a line space wheel at one end of the latter, of a supporting device carried by said platen frame and extending through said line space wheel; a pinion mounted upon said supporting device; a wheel connected to said pinion 80 and also to the line space wheel; and a wheel also connected to said pinion and to the platen; said wheels and pinion differentiating the movement of the platen from that of the line space wheel, and said line space 85 wheel having a rim portion which telescopes the platen, and one of said rim and platen elements having a cam groove and the other having a projection within said groove, for effecting endwise reciprocations of the platen. 90

95 88. In a typewriting machine, the combination of a platen frame; a hollow cylindrical platen; a line space wheel having a rim portion which projects within the platen; mechanism carried partly by said line space 95 wheel and partly by the platen for differentiating the movement of the platen from that of the line space wheel; a cam upon said rim portion; and a coöperating projection upon said platen.

100 89. In a typewriting machine, the combination with a platen of a line space wheel having internal teeth; a platen having an internal gear; a pinion connected to both said line space wheel and said platen gear and differentiating the movement of the platen from that of the line space wheel; and means carried partly by the platen for effecting endwise reciprocations of the latter.

105 90. In a typewriting machine, the combination with a cylindrical platen and a line space wheel concentric therewith, of two internal gears having unequal numbers of teeth, one fast to the platen and the other fast to the line space wheel; a toothed device rotating upon a stationary axis eccentric to the platen axis and engaging both of said internal gears; said line space wheel having a rim portion within said platen; a peripheral groove upon said rim; and a stud 110 carried by said platen and projecting into said groove.

115 91. In a typewriting machine, the combination with a platen, and a platen frame, of a line space wheel having a rim portion 120 which telescopes the platen; a cam groove in one of said rim and platen elements; a stud upon the other of said elements; and means for rotating the platen relatively to the line space wheel.

92. In a typewriting machine, the combination with a platen, and a platen frame of a line space wheel having a rim portion which telescopes the platen; a cam groove in one of said rim and platen elements, a stud upon the other of said elements, and means for rotating the platen relatively to the line space wheel; said rotating means including a gear fixed upon the edge of said rim, an 10 joining gear fixed upon the platen, and a pinion or toothed device connecting said gears.

93. In a typewriting machine, the combination with a platen frame, of a platen; a 15 line space wheel; a platen axle; a finger wheel fixed upon an end of said axle projecting from said frame; a second finger wheel between said finger wheel and said frame; and a train of gearing connecting said platen 20 to said line space wheel and operable at will by said second finger wheel to rotate the platen independently of the line space wheel.

94. In a typewriting machine, the combination with a platen frame, of a platen; a 25 line space wheel; a platen axle; a finger wheel fixed upon an end of said axle projecting from said frame; a second finger wheel; and a train of gearing connecting said platen to said line space wheel and differentiating 30 the movements of the platen from those of the line space wheel when the latter is actuated for line spacing, and also operable at will by said second finger wheel to rotate the platen independently of the line space wheel.

95. In a typewriting machine, the combination with a platen frame, of a platen; a line space wheel; a platen axle; a finger wheel fixed upon an end of said axle projecting from said frame; a second finger wheel 40 between said finger wheel and said frame; and a train of gearing connecting said platen to said line space wheel and operable at will by said second finger wheel to rotate the platen independently of the line space wheel; 45 said train of gearing being disposed wholly upon the platen side of said line space wheel.

96. In a typewriting machine, the combination with a platen frame, a platen and a line space wheel, of a revolute supporting 50 device mounted at one end upon the platen frame and projecting inwardly therefrom in line with the platen axis; a pinion mounted upon the inner end of said revolute supporting device; a wheel connected to said pinion 55 and also to the line space wheel; a wheel also connected to said pinion and to the platen; said wheels and pinion differentiating the movement of the platen from that of the line space wheel; a platen shaft extending at one 60 end through the platen frame and carrying a finger wheel at its outer end, and extending at the other end through said revolute supporting device and also carrying a finger wheel at said other end; a finger wheel fixed

upon said revolute supporting device; and 65 a friction device between said revolute supporting device and said platen frame.

97. In a typewriting machine, the combination with a platen and a line space wheel of a single train of gears connecting the 70 platen to the line space wheel and operable in one way for differentiating the movement of the platen from that of the line space wheel; and also operable in a different way for effecting movements of the platen independently 75 of the line space wheel.

98. In a typewriting machine, the combination of a platen; a line space ratchet-wheel; means for turning the latter; an internal 80 toothed member fixed to the platen, an internal toothed member fixed to the ratchet-wheel; and means in engagement with both internal toothed members, to differentiate the rotation of the platen by the normal rotation of the ratchet-wheel.

99. In a typewriting machine, the combination of a platen; a line space ratchet-wheel; a line-spacing pawl; an internal gear fixed to the platen; an internal gear fixed to the 90 ratchet-wheel; and a toothed pinion in engagement with the teeth of both internal gears, to differentiate the rotation of the platen to the normal rotation of the ratchet-wheel by the line-spacing pawl.

100. In a typewriting machine, the combination of a platen; a line space ratchet-wheel; a line-spacing pawl; an internal gear fixed to the platen; an internal gear fixed to the ratchet-wheel; and a pinion rotating on a 95 stationary axis, in engagement with both 100 said gears, to differentiate the rotation of the platen to the normal rotation of the ratchet-wheel by the line-spacing pawl.

101. In a typewriting machine, the combination of a platen; a line space ratchet-wheel; 105 means for turning the latter; two differential gears connecting the platen to the ratchet-wheel; a pinion to co-act with both gears, means to hold said pinion stationary relative to the platen axis, and means for turning 110 said pinion to effect a rotation of the platen while the line spacing wheel remains at rest.

102. In a typewriting machine, the combination of a platen; a line space ratchet-wheel; means for turning the latter; two differential 115 internal gears connecting said platen to said ratchet-wheel; a pinion to coact with said gears; and means to hold said pinion stationary relative to the platen axis.

103. In a typewriting machine, the combination of a platen; a line space ratchet-wheel; means to turn the latter; differential gears connecting the platen to the ratchet-wheel; a pinion to co-act with said gears; a shaft rotatable to control said pinion independently 120 of the line spacing wheel; and means to hold 125 said shaft against rotation by the line-spacing mechanism.

104. In a typewriting machine, the combination of a platen; a line space ratchet-wheel; means for turning the latter; differential gears connecting the platen to the ratchet-wheel; a pinion to co-act with said gears; a shaft rotatable to give said pinion a planetary motion; and means to frictionally bind said shaft to the carriage frame.
105. In a typewriting machine, the combination of a platen; a line space ratchet-wheel; means to turn the latter; differential gears connecting the platen to the ratchet-wheel; a pinion to co-act with said gears; a shaft to give said pinion a planetary motion; a finger wheel for said shaft; and means to frictionally bind said shaft to the carriage frame against rotation by the line-spacing mechanism, but to permit said shaft being turned in either direction by the finger-wheel.
106. In a typewriting machine, the combination of a platen; a line space ratchet-wheel; means for turning the latter; differential gears connecting the platen to the ratchet-wheel; a pinion to co-act with said gears; a shaft to control said pinion; and a nut to frictionally bind said shaft to the carriage frame against rotation by the line-spacing mechanism, but to permit said shaft being turned in either direction by the finger-wheel.
107. In a typewriting machine, the combination of a platen; a line space ratchet-wheel; a spring-pressed detent; an internal gear fixed to the platen, an internal gear fixed to the ratchet-wheel; a pinion in operative engagement with both gears; and means to rotate said pinion within said gears to rotate the platen independently of the ratchet-wheel and while the ratchet-wheel is at rest.
108. In a typewriting machine, the combination of a platen, a line space ratchet-wheel; a spring-pressed detent; differential gears connecting the platen with the ratchet-wheel; a pinion in operative engagement with said gears; and means to rotate said pinion within said gears, to turn the platen independently of the ratchet-wheel.
109. In a typewriting machine, the combination of a platen, a line spacing wheel, and devices for automatically varying the relation between the platen and line spacing wheel at each line spacing operation, said devices being also manually adjustable for making fine adjustments of the platen while the line spacing wheel remains at rest.
110. In a typewriting machine, the combination of a platen, a line spacing wheel, a line spacing lever, mechanism for turning the platen through an aliquant part of a complete revolution at each actuation of the line space lever, said mechanism including members wherof one may remain stationary while the others are moved at will for making fine adjustments of the platen and the paper thereon while the line spacing wheel remains at rest.

Signed at the borough of Manhattan, city of New York, in the county of New York and State of New York, this fifth day of June, A.D. 1902.

BURNHAM C. STICKNEY.
